DESIGN FOR A COOKING VESSEL

Lewis G. Howlett, Hartford, Mich., assignor to Cookware Company of America, Hartford,
Mich., a corporation of Michigan

Application December 9, 1938, Serial No. 81,687

Term of patent 3½ years

To all whom it may concern:

Be it known that I, Lewis G. Howlett, a citizen of the United States, residing at Hartford, in the county of Van Buren and State of Michigan, have invented a new, original, and ornamental Design for a Cooking Vessel, of which the following is a specification, reference being had to the accompanying drawing, forming part thereof, in which

Fig. 1 is a top plan view,
Fig. 2 is a side elevational view, and
Fig. 3 is a bottom plan view of a cooking vessel, showing my new design.

I claim:

The ornamental design for a cooking vessel,
as shown.

LEWIS G. HOWLETT.
